DESIGN FOR A BOOK CARRIER

Alwin F. Schoenfeld, Forest Hills, N. Y.

Application March 13, 1941, Serial No. 99,561

Term of patent 14 years

To all whom it may concern:

Be it known that I, Alwin F. Schoenfeld, a national of the German Reich, residing at Forest Hills, in the county of Queens and State of New York, have invented a new, original, and ornamental Design for a Book Carrier, of which the following is a specification, reference being had to the accompanying drawing, forming part thereof.

In the drawing:

Fig. 1 is a perspective view of a book carrier, showing my new design.

Fig. 2 is a front elevation thereof.

Fig. 3 is a side view of the book carrier.

I claim:

The ornamental design for a book carrier, as shown.

ALWIN F. SCHOENFELD.
